Inventor:
Frank A. Halleck.
by
Frank A. Halleck
attorney.

UNITED STATES PATENT OFFICE.

FRANK A. HALLECK, OF CHICAGO, ILLINOIS, ASSIGNOR TO SULLIVAN MACHINERY COMPANY, A CORPORATION OF MASSACHUSETTS.

FURNACE.

Application filed August 8, 1922. Serial No. 580,550.

To all whom it may concern:

Be it known that I, FRANK A. HALLECK, a citizen of the United States, residing at Chicago, in the county of Cook and State of Illinois, have invented certain new and useful Improvements in Furnaces, of which the following is a full, clear, and exact specification.

My invention relates to furnaces.

10 It has for its object to provide an improved furnace, and more especially an oil or gas furnace, wherein the size of the combustion chamber may be adjusted as desired, and whereby, as a result, by reducing the 15 size of the combustion chamber after the furnace has been heated, a more effective operation of the furnace may be obtained.

In the accompanying drawings I have shown for purposes of illustration one embodiment which my invention may assume in practice.

In these drawings,—

Fig. 1 is a transverse sectional view of a furnace equipped with my improvement, 25 showing the combustion chamber adjusted to different sizes.

Fig. 2 is a detail view showing the adjustable element and the means for holding the same in adjusted position.

30 In this illustrative construction I have shown a furnace of the type invented by one Sven T. Nelson and utilized for heating a series of blanks, the same comprising a suitable frame 1 having a substantially enclosed combustion chamber 2 therein provided with a restricted flue at the top thereof and an oil burner 3 discharging into said chamber through one wall of the same and adjacent a blank stack 4, suitable mechanism including an ejector rod 5 being used to push out the bottom blank from the stack as desired, and improved means being provided to vary the size of the chamber as hereinafter described.

45 In my improved construction, it will be observed that the chamber 2 is provided with an adjustable wall in the form of a deflector, herein the wall 6, opposite the burner 3, and that this wall is pivoted at 7 at its bottom in such manner as to enable it to be moved about its pivot from the full line position indicated in Fig. 1 to the position indicated in dotted lines in that figure, and thereby materially restrict the size of the

55 combustion chamber, any suitable means, such as bolts 8 slidably mounted on the outer surface of the wall and engageable in suitable apertures on the end walls of the chamber, being used to hold the wall 6 in its adjusted positions and also acting when in 60 their retracted position as gripping means for pulling the wall back into its upright position.

As a result of my improvement it will be observed that when the furnace has been brought up to heat and the process of combustion is proceeding smoothly, the combustion chamber may be reduced in size in such manner as to permit of increased effectiveness in operation and the concentration of 70 the heat upon the object or objects to be heated. For example, in the construction shown, it will be noted that the heat is thus concentrated upon the blanks, all necessity for heating the entire volume of the chamber being obviated. These and other resultant advantages will, however, be clearly apparent to those skilled in the art.

75 While I have in this application specifically described one embodiment which my invention may assume in practice, it will be understood that this form of the same is shown for purposes of illustration and that the invention may be modified and embodied in various other forms without departing 80 from its spirit or the scope of the appended 85 claims.

What I claim as new and desire to secure by Letters Patent is:

1. A furnace including a combustion chamber and a flue, and means to vary the size of said chamber to vary the temperature therein without varying the size of said flue.

2. A furnace including a combustion chamber and a flue, said chamber having a portion thereof pivoted in such manner as to permit adjustment to vary the size of said chamber to vary the temperature therein without varying the size of said flue.

3. A furnace including a substantially enclosed combustion chamber and a flue, said chamber having one wall thereof pivoted in such manner as to permit adjustment to decrease the size of said chamber to vary the temperature therein without varying the size of said flue.

4. A furnace including a combustion chamber having a burner in one wall there-

- of and the wall opposite said burner adjustable to decrease the size of said chamber to vary the temperature therein.
5. A furnace including a substantially enclosed combustion chamber and a flue, said chamber having a burner discharging into the same, and a wall pivoted at one edge and movable about its pivot to decrease the size of said chamber at will to 10 vary the temperature therein without varying the size of said flue.
6. A furnace including a substantially enclosed combustion chamber and a flue, said chamber having a burner discharging into the same, and an upright wall pivoted at its lower edge and adjustable to decrease the size of said combustion chamber at will to 15 vary the temperature therein without varying the size of said flue.
- 20 7. A furnace including a substantially enclosed combustion chamber and a flue, said chamber having a burner discharging into the same, and a wall pivoted at one edge and adjustable to decrease the size of said 25 combustion chamber at will to vary the temperature therein without varying the size of said flue, and means for holding said wall in adjusted position.
- 30 8. A furnace including a combustion chamber having a burner discharging into the same, work holding means disposed in said chamber, and means to vary the size of said chamber to concentrate the heat on the work.
- 35 9. A furnace including a substantially enclosed combustion chamber having a burner discharging into the same, work supporting means, and means to vary the effectiveness of said burner in heating said chamber by 40 diminishing the size of the latter while retaining a predetermined portion of the work in the heating zone.
- 45 10. A furnace including a substantially enclosed combustion chamber having a burner discharging into the same, work supporting means, and means to vary the area of said chamber adjustable to vary the size of the top of said chamber while retaining a predetermined portion of the work 50 in the heating zone.
- 55 11. A furnace including a substantially enclosed combustion chamber having a burner discharging into the same, work supporting means, and a member in said chamber adjustable to vary the effectiveness of said burner in heating said chamber after the latter has been brought up to heat while retaining a predetermined portion of the work in the heating zone.
- 60 12. A furnace including a substantially enclosed combustion chamber having a burner discharging into the same, and a deflector in said chamber disposed opposite said burner adjustable to vary the effectiveness of said burner in heating said chamber 65 after the latter has been brought up to heat.
13. A furnace including a substantially enclosed combustion chamber having a burner discharging into the same, work holding means in said chamber opposite said burner, and means to vary the effectiveness of said burner in heating said chamber and concentrate the heat on the work after the chamber has been brought up to heat. 70
14. A furnace including a combustion chamber having a burner discharging into the same, work holding means in said chamber, and a deflector opposite said burner to vary the effectiveness of said burner in heating said chamber and concentrate the heat on the work after the chamber has been brought up to heat. 75
15. A furnace including a substantially enclosed combustion chamber having a burner discharging therein, and a wall disposed opposite said burner and pivoted at one edge thereof and movable about its pivot in a direction toward the burner discharge to decrease the size of said chamber at will to vary the temperature therein. 80
16. A furnace including a substantially enclosed combustion chamber having a burner in one wall thereof discharging therein, and an upright wall opposite said burner pivoted at its lower edge and adjustable to decrease the size of said chamber at will to vary the temperature therein. 85
17. A furnace including a combustion chamber having a burner discharging therein, a wall pivoted at one edge and adjustable to decrease the size of said chamber at will to vary the temperature therein, and means including a reciprocable member for holding said wall in its adjusted positions. 90
18. A furnace including a substantially enclosed combustion chamber having a restricted flue, and an adjustable element to decrease the area of said chamber to vary the temperature therein without varying the size of said flue. 100
19. A furnace including a substantially enclosed combustion chamber having a restricted flue and a burner discharging therein, and an adjustable element opposite said burner to decrease the area of said chamber to vary the temperature therein without varying the size of said flue. 110
20. A furnace having a substantially enclosed combustion chamber and a blank stack support therein, and an adjustable member movable in a direction toward said blank stack support to vary the temperature of the blanks in said stack. 120
21. A furnace having a substantially enclosed combustion chamber and a burner discharging therein, a blank stack support in said chamber, and an adjustable member movable in a direction toward said burner and said blank stack support to increase the temperature of the blanks in said stack. 125

22. A furnace having a substantially enclosed combustion chamber and a burner discharging a flame therein, and a movable flame deflecting member disposed directly in the path of the flame and adjustable to vary the effectiveness of said burner in heating said chamber.

23. A furnace including a substantially

enclosed combustion chamber provided with a restricted flue and having an adjustable element movable to vary the size of said chamber to vary the temperature therein without varying the size of said flue. 10

In testimony whereof I affix my signature.

FRANK A. HALLECK.
